UNITED STATES PATENT OFFICE.

ARTHUR E. KENYON, OF BARRE, MASSACHUSETTS.

CALCULATING-MACHINE.

No. 824,795.

Specification of Letters Patent.

Patented July 3, 1906.

Application filed November 11, 1903. Serial No. 180,660.

To all whom it may concern.

Be it known that I, ARTHUR E. KENYON, a citizen of the United States, residing at Barre, in the county of Worcester and State of Massachusetts, have invented a new and useful Calculating-Machine, of which the following is a specification.

My invention relates to that class of calculating-machines in which the results are obtained upon a series of figure wheels or dials operated by keys. While the same is adapted to various classes of arithmetical computation, it is designed more especially for commercial accounting.

My object is to provide a small compact machine of the class above stated of such dimensions that it can be conveniently placed upon an account-book for checking items, footing accounts, &c., and to reduce the keys to a number easily operated by one hand without changing the position thereof, so that any key can be accurately and instantly located without detracting the operator's attention from the accounts or notes. By this arrangement a machine is provided which will add columns or scattered items with despatch. The mechanism may be and preferably is also arranged so that addition or subtraction can be performed with precisely the same reading of the keys and exactly the same movement of the hand, so that the operator does not have to distinguish between the operation of adding or the operation of subtracting, thereby avoiding errors arising from force of habit. By the arrangements hereinafter described a thoroughly universal calculating or accounting machine is provided.

The mechanism is illustrated in the accompanying three sheets of drawings, referring to which—

Figure 1 is a plan view of the mechanism with the cover-plate removed. Fig. 2 is a cross-sectional view taken just inside the right-hand end of the frame. Fig. 3 is a plan, Fig. 4 is a side view, and Fig. 5 is an end view, of one of the operating-keys. Fig. 6 is a diagram illustrating the action of the keys. Fig. 7 is a sectional elevation, and Fig. 8 is an end elevation, of the mechanism used in connection with the registering-dials. Fig. 9 is a front detail view, and Fig. 10 is a side view, of the mechanism which sets the machine to either add or subtract. Fig. 11 is a view illustrating the stop used on the cam-shaft.

Fig. 12 is a detail view illustrating the return-spring for the cam-shaft. Fig. 13 is a detail view illustrating the pawl releasing or setting mechanism, and Figs. 14 and 15 are detail views of the parts making up the pawl-releasing mechanism. Fig. 16 is a fragmentary view illustrating the parts making up one of the dials. Fig. 17 is a view illustrating the clutch connection on the dial-shaft. Fig. 18 is a view illustrating one of the ratchet-arms connected to the dials, and Figs. 19, 20, and 21 are detail views illustrating a modification hereinafter referred to. Fig. 22 is a detailed perspective view showing the devices for shifting the dial-clutches.

The operation of the mechanism can best be understood by first describing the various mechanisms in detail.

A designates the casing, which usually is made out of metal with the proper bearings or hubs. Journaled in the framing is a key-shaft B, a cam-shaft C, and a dial-shaft D. The various mechanisms are principally arranged upon these three shafts.

Referring now to the construction of the key-shaft, it will be seen that arranged loosely on the same is a cylinder or shell 10, which has projections 11. Fitting on this shell are the hubs 12 of the operating-keys. These hubs are slotted so that each will engage a projection 11 of the shell 10, and, if desired, a screw 13 can be inserted in each hub to provide for adjustment and to make the hubs a strong structure. The normal arrangement of the parts is that shown in Fig. 4. The hub 12 of each key is cut away, as at 14. A key 15 is inserted in the key-shaft B. This key has projections 16, which when the parts are assembled project into the slots 14 in the hubs of the keys. The parts can be assembled by first putting the key into the shaft B, so that the projections 16 will come into the slots 14 of the keys and by then inserting shell 10. Projecting from each key-hub is a key-arm 17.

Arranged on each key-arm 17 is an engaging slotted flanged ring 18. These rings are set to different positions on the respective arms—that is to say, as there are nine keys in the structure under consideration there will be nine different positions of these slotted rings on the nine keys relatively to the projections 16, as indicated in Fig. 6. The position of the ring 18 on key No. 8 is indicated in Fig. 4. By this arrangement a different

relative movement is imparted to the shaft B from each key. These rings 18 are set on the key-arm 17 so that the movement imparted to the shaft by key No. 9 will be nine times that imparted thereto by key No. 1, although the downward movement of each key as a whole is the same. The intermediate keys between one and nine have the rings properly set to get the desired ratio. The end of each key-arm 17 is bifurcated, and fitting in the same is the projecting shank 19 of the finger-piece 20, a pin 21 keeping the parts in position. The shank 19 is provided with a stop 22 to engage a stop 23 on the end of the key-arm 17 to limit the movement of the finger-piece in one direction upon the pin 21. Springs 24 are arranged in the framing to engage ears 240 on finger-pieces, as shown in Fig. 2, so as to keep the keys normally elevated. Each key-arm works in a slot 25 cut in the framing, the bottom of the slot limiting the downward movement of the keys. A zero-key has arms fitting between the sixth and seventh and the seventh and eighth keys, as shown. These arms simply engage the shell 10 and have no mechanism to engage or operate the shaft B.

By the above-described arrangement it will be seen that when any key is depressed and brought to the bottom of its slot a movement will be imparted to the shell 10 which is the same for all keys; but a movement will only be imparted to the shaft B measured by the adjusted position of the ring 18 on the particular key-arm, so that the movement imparted to the shaft B will be a measured movement, determined by the value of the key. The shell 10 is arranged to operate or set the cam-shaft C, as hereinafter described, and the shaft B is arranged to operate the dial-shaft D, as hereinafter described. The construction of the cam-shaft C and the operating connections to the same from the shell 10 will now be described.

Arranged tightly on the cam-shaft C are a series of nine face-cams 26, each of which has a notch in its side. The cams are set on the shaft C so that these notches come in radial progression by tenths, or one more than the number of the cam on the shaft. A pin 27 projects from the shaft C and is arranged to strike a projection 28 in the bottom of the framing to define the normal position of the cam-shaft, as shown in Fig. 11. A spiral or clock spring 29 is housed in a shell and is connected to said shaft C and to a stationary part, so as to tend normally to return the shaft C to the position shown in Fig. 11. This spring is shown in detail in Fig. 12. The right-hand cam 26 is additionally used to form an operating ratchet-wheel 30 with ten teeth. On the right-hand end of the shell 10 is arranged a hub with a projecting arm 31. A spring or laterally-acting pawl 32 is arranged on this arm in position to engage the

ratchet-wheel 30. A spring or laterally-acting holding-dog 33 is arranged to hold the ratchet-wheel in its set position. By the connection thus described, and as the shell 10 is given the same movement for the operation of any key, it will be seen that the ratchet-wheel 30, and therefore the cam-shaft C, is given the same movement for each key depressed. The ratchet-wheel 30 is provided with ten teeth, and the parts are so arranged that every time a key is struck the ratchet-wheel will be turned one-tenth of a revolution. The zero-key imparts the same movement to the ratchet-wheel 30 as the other keys. By this cam-shaft and the mechanisms hereinafter described operative connection is made to the proper dial-wheel.

A releasing mechanism is necessary to allow the cam-shaft to return to normal position after a given number has been set up on the keys. This releasing mechanism is arranged as follows: A release or set key 34 has arms projecting through the casing, one of which is merely a guide-arm and the other an operating-arm, as shown in Fig. 13, suitable springs being arranged to keep the key normally elevated. The operating-arm 35 of said key connects to an arm 36, pivoted on a small shaft fitted in a bracket 37 arranged in the framing. An arm 38 also projects from said shaft and connects to an arm 39, arranged on a ratchet-detacher 40. This ratchet-detacher 40 is made from a steel stamping originally cut out, as shown in Fig. 14, and then bent, as shown in Fig. 15. The end of the same thus forms a disk 41, which has a hole through which the cam-shaft C projects. The disk is housed within the ratchet-wheel 30.

When the release-key is depressed, the disk 41 will be moved to the right and will throw the pawl 32 and the holding-dog 33 out of engagement with the ratchet-wheel 30 and will allow the spring 29 to return the cam-shaft C to the normal position shown in Fig. 11. By this arrangement as each key is operated, starting from normal position, the cam-shaft will be given a tenth revolution, and when the release or set key is operated the cam-shaft will be allowed to spring back to normal position.

The construction of the dial-shaft D and its operating connections to the key-shaft B and the cam-shaft C will now be described. Secured on the right-hand end of the key-shaft B is an arm 42, which is pulled to the right, as shown in Fig. 2, by a spring 43. Extending from this arm is a rack 44, which engages a clutch wheel or gear 45, arranged on the shaft D. The movement of this rack, and therefore the movement imparted to the gear, is a movement measured by the character of the key by reason of the construction of the keys before described. On the other end of the key-shaft B is arranged an arm 46,

(see Fig. 1,) which is pulled to the right, as Fig. 2 stands, by the spring 43. A rack 48 is connected to this arm and engages a clutch-gear 49, also secured on the shaft B. Suitable guiding means are provided to keep the rack 44 and gear 45 and rack 48 and gear 49 in proper engagement. It will be noticed that the rack 44 engages the top of the gear 45 and that the rack 48 engages the under side of the gear 49. Hence the movement imparted to the respective gears 45 and 49 by the operation of a key will be in relatively opposite directions.

When it is desired to use the machine to add, the rack 44 and gear 45 are used as the operative members, and when it is desired to use the machine for subtraction the rack 48 and gear 49 are employed. A setting mechanism is provided, so that the machine can be used for either operation. In this setting mechanism 50 and 51 designate two shifters arranged on a rod 52, which can slide in the framing. The shifter 50 constitutes a projecting arm which engages a groove cut in a clutch 53, keyed to the shaft D. The clutch-gear 45 is loosely arranged on said shaft D and has teeth arranged to engage the teeth of the clutch 53. By this construction when the rod 52 is shifted to the right the gear 45 will be connected to the shaft D. The other shifter 51 constitutes a projecting arm which engages a clutch 54, keyed on the left-hand end of the shaft D. The clutch-gear 49 is arranged loosely on the shaft D and has teeth to engage the clutch 54. By this arrangement when the rod 52 is shifted to the left the gear 49 will be connected to the shaft D. By this arrangement either of the trains of connecting mechanism at the right or the left of the key-shaft B can be used to actuate the key-shaft D.

A mechanism is provided to shift the rod 52 and is arranged as follows, (see Figs. 9 and 10:) A key 55, having the word "Subt." thereon, projects up through the casing. A similar key 56, having the word "Add" thereon, also projects through the casing. These keys are connected to a curved indicator 57, on which is placed the words "Add" or "Subt." This indicator is arranged to show through a notch cut in the casing so as to indicate which operation the machine is adjusted for. The two keys 55 and 56 connect at their ends to a rocking piece 58, arranged on a suitable stud. This rocking piece has a bifurcated arm 59, which engages a pin 60 on the sliding rod 52, so that as either key 55 or 56 is operated the rod will be moved to connect either of the clutches, as hereinbefore described. The rocking piece 58 is provided with a crown-wheel 61, which meshes with an intermediate 62, which latter engages a pinion 63 on a slabbed setting-shaft 64. (See Fig. 8.) The intermediate 62 is arranged on a shaft 65, fitted in

the casing. A shaft 66 is also fitted in the casing. Secured to and projecting up from the shaft 66 are bearing-pieces 67, one being arranged for each cam on the shaft D. The slabbed setting-shaft 64 passes freely through these bearing-pieces 67.

The construction of one of the dials will now be described. Reference should be had to Figs. 7, 8, 16, 17, and 18. Each dial 68 has nine numbers and a zero on its periphery and a notch 69 cut in its side. Adjacent to each dial are arranged cams 70 and 71 and ratchet-wheels 72 and 73. The cams 70 and 71 are arranged at the left of the dial and the ratchet-wheels 72 and 73 at the right. The cams 70 and 71 are notch-cams oppositely arranged, and the ratchets 72 and 73 each have ten teeth and are arranged oppositely. These five parts (shown in Fig. 16) are rigidly driven on a shell 74. Driven tightly in the shell 74 is one section 75 of a clutch. The other section 76 of this clutch is tightly fitted on the shaft D. The clutch-section 75 turns loosely on the clutch-section 76.

A sliding clutch 77 is loosely arranged on the shaft D and has fine teeth on its left-hand face to connect the teeth on the right-hand faces of the clutch-sections 75 and 76. When the clutch 77 is disconnected from the clutch-sections 75 and 76, as shown in Fig. 17, the dial and its various parts can turn on the clutch-section 75; but when the clutch 77 engages clutches 74 and 75 the parts shown in Fig. 16, mounted on the shell 74, are connected to shaft D. The clutch-sections 75 and 76 are made to turn with some friction on each other, so that there will be no liability for an accidental movement of the dials, or, if desired, any of the ordinary holding-pawls can be used in connection with the ratchet-wheels 72 and 73.

The bearing-pieces 67 are slotted at 670 on their front sides, and working through each slot is the projecting bent end of an arm 78, which is mounted on pivot-screw 79, secured in the proper bearing-piece 67, said end 780 engaging in a peripheral groove 770 in clutch member 77. Each arm 78 at its lower end has a bent portion engaging one of the cams 26 on shaft C, and a suitable spring 80 is arranged to keep this bent section normally against its cam. Each cam has a spot 81 thereon. Each of these spots shows through hole 82, cut in the casing, as shown in Fig. 2, there being a series of holes 82, one for each cam. The spot is arranged on each cam, so that when the spot appears through the hole that particular cam will be in operative position.

When any cam is in operative position, the lower projecting end of the arm 78 will swing into the notch of the cam, and the arm 78 will thereby throw the sliding clutch 77 to the left and lock the particular dial and the parts shown in Fig. 16 to shaft D. It is nec-

essary to put an operative connection between the dials, and this is the purpose of the ratchet-wheels and cams before referred to. Pivoted on a screw 83, secured in each bearing-piece 67, are two ratchet-arms 84 and 85, which are respectively arranged as rights and lefts, as shown in Fig. 8. The ratchet-arm 84, nearest the bearing-piece 67, is arranged to engage the ratchet-wheel 73, and the other ratchet-arm 85 is arranged to engage the ratchet-wheel 72, the arms 84 and 85 projecting oppositely relatively to the screw 83. The ratchet-arm 85 has a depending arm 86, and the ratchet-arm 84 has a similar depending arm 87, bent to come opposite arm 86.

A spring 88 is arranged normally to force the arms 86 and 87 toward each other. These arms 86 and 87 engage the slabbed setting-shaft 64. This shaft 64 is slabbed, as shown in Fig. 8, so that when it is turned in one position, as for addition, the ratcheting-arms 84 will be operative, but so that when it is turned to the other position the ratcheting-arms 85 will be operative.

Projecting toward the left hand in Fig. 1 from the arm 85 is a finger 89, which extends in position to engage the cam 70 of the next dial at the left. A finger 90 projects to the right from the arm 84 to engage the cam 71 of the next dial at the right. The arms 84 and 85 are provided with spring-pressed pawls 91 to operate the ratchet-wheels. With this device when the machine is set for addition the slabbed shaft 64 will be moved to the position shown in Fig. 8, so that only the ratcheting-arms 84 are operative. When any particular dial has moved around through all its numbers to the zero-point, its cam 71, turning therewith, on which the finger 90 presses, will allow the arm 84 to move in to turn the ratchet 72 of the dial at the left one notch. This same construction is used between all the dials, so that every time a dial passes the zero-point the dial in advance or at the left in Fig. 1 will be moved one notch. If, on the other hand, the "Subt." hand is pressed, the shaft 64 is turned one hundred and eighty degrees, and the arms 84 are moved outwardly, and the arms 85 are allowed to come into position for operation. If now one of the dials passes through the zero-point, the cam 70 thereof will operate the finger 89, and thereby the cam 85, to move the ratchet-wheel 73 of the dial at the right one notch. Hence in subtracting the dial at the right will be moved one notch or figure as the dial at the left moves through the zero-point.

To set the dials to normal position, a comb or rubber shaft 92 is mounted in arms 93, pivoted on rod 52 and held normally back out of the way by a spring 94.

Extending between the arms 93 is a piece 95, which has little spring-teeth 96 projecting therefrom to engage notches 97, cut on the

side of each dial. These notches are arranged in such position that the teeth will engage the notches when the dial stands at zero. The comb is provided with a knob 98. By moving the comb into engagement with the dials 70 and by then turning the same in bearing engagement with the dials they can all be brought to zero position, as when they reach this position the teeth 96, engaging the notches 97, will prevent further movement of 75 the dials. When the comb is allowed to move back out of the way, the teeth become inoperative.

The operation of this mechanism is as follows: If it is desired to use the machine for addition, the add-key is depressed, bringing the shaft 64 to the position shown in Fig. 8 and bringing the ratcheting-arms 84 into operative position. The set or release key is struck to allow the cam-shaft C to take its 80 normal position. Now suppose that the first number we wish to use is "123,456,789." Instead of starting at the left of said column to set said figure down we start at the right and press the "9" key first, which by the mechanism before described will set the dial 26 at the right at "9" and will turn the cam-shaft one notch.

In the next operation the second dial will be in operative position, and as the "8" key is 95 depressed it will be set to its eighth position and the cam-shaft advanced one notch, so as to bring the third dial into operative relation with the cam-shaft. The succeeding numbers are then struck in the regular order, 100 reading from right to left. By this operation the dials will be set to indicate the figure which it was desired to start with. After this figure is set down the release-key is struck, bringing the cam-shaft back to its 105 normal position. The next number is then set down by the keys in the manner before described, starting with the units, then the tens, hundreds, &c., the principle of the machine being to set the figure down reading 110 from the right to the left. As this second figure is set down the same is added to the first figure. By this arrangement addition can be performed up to the limits of the machine, which is determined by the number of 115 dial-wheels, which in the particular machine illustrated is nine.

It will be observed that by reason of the direction of the teeth on the clutch members 53 and 54 the dial-shaft will be operated on 120 the up or return stroke of the rack-bar, so that with each operation of a key the previously-locked dial will be first unlocked, then the adjacent dial will be locked, and then as the key rises the dial-shaft will be turned a 125 distance corresponding to the digital value of the particular key struck. This arrangement is advantageous in that it enables me to do away with gearing and to employ a very compact and reliable mechanism and to 130

provide for adapting the machine for subtracting and for multiplying by the addition of but a few simple parts.

If an error is made on any dial, the same can be corrected by turning the cam-shaft manually by means of the hand-wheel C' until the spot on the particular cam wanted appears through the holes in the casing, when by using either the adding or subtracting key 10 the error can be corrected. When the problem is finished, the comb is used to set the dials at zero.

When it is desired to subtract, the number from which the subtractions are to be taken 15 is first set down with the addition-key depressed, and the subtract-key is then depressed, bringing into the operation the ratcheting-arms 85. The keys are now operated as before described, reading each number it 20 is desired to subtract from right to left. With each operation the number called will be subtracted from the original number set down. In some cases it is additionally desired to use the machine for multiplying. In 25 this case the zero-key is placed at the right of the key No. 1 and the construction used in Figs. 19 to 21 is employed. The end of the shell 10 is formed into a clutch 100.

Sliding loosely on the end of the shaft B is 30 a hub 101, which has clutch-teeth to engage said clutch 100. This hub-clutch slides inside of a sleeve 102. The sleeve 102 is slotted, and fitted to the slot is a block 103, connected to which is an arm 104, which projects out through the side of the casing and which has an operating-button 105 on its end. In this arrangement the arm 31, which carries the pawl 32 to operate the ratchet-wheel 30, is made part of the hub 102. By means 35 of the block 103 it will be seen that the zero-key and the shell can be connected to turn together by pushing in on the button 105.

When the device is to be used for addition or subtraction, as previously described, the 40 hub-clutch 101 then engages with the clutch 100. The operation is then the same as previously described. When the clutch 101 is in engagement with the clutch 100 on the end of the shell 10 for either operation of addition or subtraction, it will be noted that the movement of the shell 10 does not move the zero-key, for as the shell 10 is moved it will move the clutch-hub 101 and through the block 103 the hub 102, which carries the arm 45 31; but this will be a movement of the block 103 away from the key, which will not operate the same, the key-hub being cut away at its bottom, as shown in Fig. 21, for this purpose. When the zero-key is struck by itself, 50 the key-hub will push on block 103 and the pawl-arm 31 will operate the ratchet-wheel 30, but the shaft B will not be operated.

When the device is to be used for multiplication, the button 105 is pulled out, releasing the hub of the zero-key from the shell 55

10. When the parts are in this position, if the zero-key is depressed it will bear on the block 103 and will operate the hub 102 to actuate the arm 31, the clutch 101 being in idle position and not engaging the shell 10.

Now suppose it is desired to multiply two numbers together—as, for example, 456 by 123. Starting with the dials in zero position and with the cam-shaft C in normal position, the key No. 6 is struck three times. The zero-key is then struck. Key No. 5 is then struck three times. The zero-key is then struck, and key No. 4 is then struck three times. This will set "456" down three times, or "1368." The release-key is then operated. The zero-key is then operated so as to start the next operation in tens. Key No. 6 is struck twice, the zero-key struck, key No. 5 is struck twice, the zero-key struck, and key No. 4 struck twice. This will add to the previous 85 figure twenty times four hundred and fifty-six. The release-key is then struck and the zero-key is struck twice, so as to start at the hundredths. Key No. 6 is then struck once, then the zero-key struck. Key No. 5 is then 90 struck once, then the zero-key struck. Key No. 4 is then struck once. This will add to the previous obtained product one hundred times four hundred and fifty-six. The resulting product will now be one hundred and 95 twenty-three times four hundred and fifty-six, the desired result. If a zero is encountered in the multiplicand, the same is passed over by simply striking an additional zero at the desired point. If a zero is encountered 100 in the multiplier, the same is provided for by simply striking an additional zero when passing to the next figure to the left of the multiplier.

In these hereinbefore-described operations 105 to perform the problem of multiplication it will be seen that the function of the zero-key is simply to bring the proper cam 26 into operative position, or, in other words, to connect the keys to the proper dial. As the 110 keys are released from the projecting arm 31 during this operation the successive operation of each key for the purpose of multiplication has no effect upon the cam-shaft, and therefore does not disturb the dials. With 115 this attachment and with a little experience long and complicated problems of multiplication can be performed.

While I have shown the machine in the principal figures of the drawings arranged to 120 perform either addition or subtraction, it is obvious, of course, that those parts which go to adapt the machine for either the process of addition or subtraction could be eliminated and a simple machine constructed under the principles of my invention to add alone or to subtract alone.

The broad combinations which I express in my claims can be used for an adding mechanism which is well adapted for many purposes 130

besides that of a calculating-machine—such, for example, as the adding mechanism in a cash-register or other similar device.

The details of the mechanism have been so fully described that further description of the operation as a whole is not believed necessary. The number of dials used and the relative arrangement of the parts may be varied by a skilled mechanic without departing from the scope of my invention as expressed in the claims.

Having thus fully described my invention, what I claim, and desire to secure by Letters Patent, is—

1. In a calculating-machine, the combination of a series of numbered keys, a dial-shaft and devices whereby the operation of any key will rotate the dial-shaft a distance corresponding to the digital value of the key struck, a series of independent dials normally loosely revoluble on the dial-shaft, and mechanism whereby a dial is first locked to the dial-shaft during a key operation and then turned and the operation of each subsequent key will first release the locked dial and then lock and turn the next adjacent dial, whereby one of the dials will remain locked to the shaft during each operation in addition or subtraction.

2. In a calculating-machine, the combination of a series of numbered keys, a dial-shaft and devices whereby the operation of any key will rotate the dial-shaft a distance corresponding to the digital value of the key struck, a series of independent dials normally loosely revoluble on the dial-shaft, and mechanism whereby a dial is first locked to the dial-shaft during a key operation and then turned and the operation of each subsequent key will first release the locked dial and then lock and turn the next adjacent dial, whereby one of the dials will remain locked to the shaft during each operation in addition or subtraction, and means whereby the dial-locking mechanisms may be successively manually operated independently of the key mechanism for the purpose of making corrections.

3. In a calculating-machine, the combination of a series of numbered keys, a dial-shaft and devices whereby the operation of any key will rotate the dial-shaft a distance corresponding to the digital value of the key struck, a series of independent dials normally loosely revoluble on the dial-shaft, and mechanism whereby a dial is first locked to the dial-shaft during a key operation and then turned and the operation of each subsequent key will first release the locked dial and then lock and turn the next adjacent dial, whereby one of the dials will remain locked to the shaft during each operation in addition or subtraction, means whereby the dial-locking mechanisms may be successively manually operated independently of the key mechanism for the

purpose of making corrections, and means for indicating which dial is locked.

4. In a calculating-machine, the combination of a series of numbered keys, a dial-shaft and devices whereby the operation of any key will rotate the dial-shaft a distance corresponding to the digital value of the key struck, a series of independent dials normally loosely revoluble on the dial-shaft, and mechanism whereby a dial is first locked to the dial-shaft during a key operation and then turned and the operation of each subsequent key will first release the locked dial and then lock and turn the next adjacent dial, whereby one of the dials will remain locked to the shaft during each operation in addition or subtraction, and means whereby the dial-locking mechanisms may be successively manually operated independently of the key mechanism for the purpose of making corrections, and restoring means for normally adjusting the dial-locking devices so that all the dials shall stand normally released.

5. In a calculating-machine, the combination of a series of numbered keys, a dial-shaft and devices whereby the operation of any key will rotate the dial-shaft a distance corresponding to the digital value of the key struck, a series of independent dials normally loosely revoluble on the dial-shaft, and mechanism whereby a dial is first locked to the dial-shaft during a key operation and then turned and the operation of each subsequent key will first release the locked dial and then lock and turn the next adjacent dial, whereby one of the dials will remain locked to the shaft during each operation in addition or subtraction, and means whereby the dial-locking mechanisms may be successively manually operated independently of the key mechanism for the purpose of making corrections, restoring means for normally adjusting the dial-locking devices so that all the dials shall stand normally released, and key-operated means for releasing the restoring devices.

6. In a calculating-machine, the combination of a series of numbered keys, a dial-shaft and devices whereby the operation of any key will rotate the dial-shaft a distance corresponding to the digital value of the key struck, a series of independent dials normally loosely revoluble on the dial-shaft, and mechanism whereby a dial is locked to the dial-shaft by an operation of a key and before the shaft is operated and the operation of each subsequent key will release the locked dial and then lock the adjacent dial before it is turned, said mechanism embodying a clutch for each dial and means for shifting the clutches into engagement with the dials in succession.

7. In a mechanism of the class described, the combination of a key-shaft, a shell fitted thereon, a series of keys fitted on the shell, means whereby each key will impart a meas-

ured movement to the key-shaft depending upon the number of the key and whereby each key will impart the same movement to the shell, a series of dials, connections from 5 said shell to operate the dials in turn, and connections from said key-shaft to impart a measured movement to the particular dial brought into operation.

8. In a mechanism of the class described, 10 the combination of a key-shaft, a shell arranged thereon, a series of keys mounted on the shell, means whereby said keys are arranged to impart a measured movement to said shaft depending on the number of the 15 key and each key the same movement to the shell, a cam-shaft having a series of cams arranged in radial progression thereon, a dial-shaft having a series of dials arranged thereon, connections from said shell to operate 20 said cam-shaft, connections from said key-shaft to operate the dial-shaft, and connections from said cams to lock the dials in turn to the dial-shaft.

9. In a mechanism of the class described, 25 the combination of a key-shaft, a shell arranged thereon, a series of keys arranged on said shell, means whereby each of the series of keys will impart a measured movement to the key-shaft determined by the number of 30 the key and each key the same movement to the shell, a cam-shaft having a series of cams arranged thereon in radial progression, a dial-shaft carrying a series of dials, connections from the cam-shaft to lock the dials in turn 35 to the dial-shaft, connections from the shell to operate the cam-shaft, and connections from the key-shaft to operate the dial-shaft in either direction, as desired.

10. In a calculating-machine, the combination 40 of a series of numbered keys, a dial-shaft and devices whereby the depression of any key will rotate the dial-shaft a distance corresponding to the digital value of the key struck, a series of independent dials loosely 45 revolute on the dial-shaft, and mechanism whereby one dial is locked to the dial-shaft during the operation and the depression of any one key will release the locked dial after it is turned a distance corresponding to the 50 digital value of the key struck and lock the next adjacent dial to the dial-shaft, said mechanism embodying a clutch for each dial, a shaft carrying a cam for each clutch, means whereby each cam operates one of the 55 clutches and means whereby the cam-shaft may be operated through the medium of the keys or independently thereof.

11. In a calculating-machine, the combination 60 of a series of numbered keys, a dial-shaft and means whereby the depression of any key will rotate the dial-shaft a distance corresponding to the digital value of the key struck, said devices embodying reversely-arranged clutches and pinions on the dial-shaft

and reversely-arranged rack-bars engaging 65 said pinions, substantially as set forth.

12. In a mechanism of the class described, 70 the combination of a key-shaft, a shell fitted thereon, a series of keys fitted on the shell, means whereby each key will impart a measured movement to the key-shaft, depending upon the number of the key, and the same movement to the shell, a cam-shaft having a series of cams arranged in radial progression, 75 connections from the shell to operate the cam-shaft, a dial-shaft, a series of dials arranged thereon, two sets of connections from the key-shaft to operate the dial-shaft, connections from the cam to bring the dials into successive operation, two series of ratcheting 80 mechanisms arranged between the dials, and means whereby the proper ratcheting device is brought into operation in connection with the two sets of connections from the key-shaft. 85

13. In a mechanism of the class described, 90 the combination of a key-shaft, a shell fitted thereon, a series of keys fitted on the shell, projections from the shell engaged by the keys at the same point, and connections from the key-shaft engaged by the keys at different points determined by the number of the key.

14. In a mechanism of the class described, 95 the combination of a key-shaft, a shell mounted thereon having projections, a series of keys mounted on the shell and engaging said projections at the same point, projections extending from the shaft, and an adjustable ring carried by each key to engage a 100 projection extending from the shaft and arranged so that the same can be set so that each key will impart the proper movement determined by its number to said key-shaft.

15. In a mechanism of the class described, 105 the combination of a key-shaft, an extending bifurcated key-arm, a finger-piece fitted therein, stops for limiting the movement of the finger-piece, and a spring engaging the finger-piece to keep the key in normal position. 110

16. In a mechanism of the class described, 115 the combination of a key-shaft, a shell fitted thereon, a series of keys arranged on the shell and engaging the same at the same point, a series of projections extending from the key-shaft, means whereby the keys engage the same in measured ratio, determined by the number of the key, and a zero-key fitted to and operating said shell without operating said shaft. 20

17. In a calculating-machine, the combination 125 of a series of numbered keys, a dial-shaft and means whereby the operation of any key will rotate said shaft a distance corresponding to the digital value of the key struck, said devices embodying a pair of pinions on the dial-shaft, reversely-arranged clutches, re-

versely-arranged rack-bars engaging said pinions, and means for shifting either clutch out of action, whereby the machine may be adapted for subtracting or for adding as occasion may require.

18. In a mechanism of the class described, the combination of a cam-shaft having a series of cams for the purpose stated, a spring for returning the cam-shaft to normal position, a ratchet-wheel for operating the cam-shaft, an operating-pawl therefor, a holding-dog for holding the ratchet-wheel in set position, a set-key, and connections therefrom to throw said pawl and holding-dog out of engagement with the ratchet-wheel to allow the cam-shaft to return to normal position.

19. In a mechanism of the class described, the combination of a cam-shaft, having a series of cams for the purpose stated, a ratchet-wheel for operating said cam-shaft, a spring for returning the same to normal position, an operating-pawl and a holding-dog for the ratchet-wheel, a disk housed within the ratchet-wheel, a set-key, and connections therefrom to said disk whereby the operating-pawl and holding-dog can be thrown out of engagement with the ratchet-wheel and the cam-shaft allowed to return to normal position.

20. In a mechanism of the class described, the combination of a dial-shaft, a series of dials loosely arranged thereon, a ratchet-wheel and a cam turning with each dial, a pawl for each ratchet-wheel, a connection therefrom to the cam on the next dial, and means for successively connecting the dials to the dial-shaft.

21. In a mechanism of the class described, the combination of a dial-shaft, a series of dials loosely arranged thereon, two ratchet-wheels and two cams turning with each dial, a pawl for engaging each ratchet-wheel, a connection from each pawl to the cam on the next dial in advance, a connection from the other pawl to the cam on the dial in the rear, means whereby either set of pawls can be brought into operation, and means for successively connecting the dials to the dial-shaft.

22. In a mechanism of the class described, the combination of a dial-shaft, a series of dials loosely arranged thereon, each dial having two cams and two ratchet-wheels turning therewith, a pawl for each ratchet-wheel, a connection therefrom to the proper cam, two operating means for the dial-shaft, a clutch for bringing either into operation, and means for operating said clutches and at the same time throwing the proper ratchet mechanism into operation.

23. In a mechanism of the class described, the combination of a dial-shaft, a series of dials loosely arranged thereon, two sets of ratchet mechanisms for the dials, means for

bringing the dials into successive connection with the dial-shaft, two operating means for the dial-shaft, and means for bringing either into operation together with the proper ratchet mechanisms, said means consisting of two connected keys and connecting to said operating means and to said ratchet mechanisms.

24. In a mechanism of the class described, the combination of a dial-shaft, a series of dials loosely arranged thereon, means for bringing the dials into successive operation with the dial-shaft, two ratchet mechanisms for the dials, two operating means for the dial-shaft, clutches for connecting the same to the dial-shaft, and a mechanism for bringing the same into operation together with the proper ratchet mechanism consisting of two connected keys, connections therefrom to control the clutches, and a slotted shaft operated thereby controlling the ratchet mechanisms.

25. In a mechanism of the class described, the combination of a dial-shaft, a series of dials arranged thereon, two ratchet-wheels and two cams connected to each dial, a pawl engaging each ratchet-wheel, pivoted arms carrying said pawls, fingers extending from said arms to engage the proper cams, a spring for pulling said arms toward the ratchet-wheels, and a slotted shaft engaging said arms for bringing either of the sets of pawls into operation.

26. In a mechanism of the class described, the combination of a cam-shaft, a series of cams arranged thereon in radial progression, a dial-shaft, a series of dials loosely arranged thereon, a clutch for connecting each dial to the dial-shaft, and a connection from each cam to each clutch.

27. In a mechanism of the class described, the combination of a dial-shaft, a series of notched dials arranged thereon, means for bringing the dials back to normal position consisting of a comb-roller which can be brought into engagement with the dials and a piece having teeth engaging the dials to hold them in normal position.

28. In a mechanism of the class described, the combination of a cam-shaft, a series of cams arranged thereon for the purpose described, a spot on each cam, and holes through the casing for determining which cam is in operative position.

29. In a mechanism of the class described, the combination of a key-shaft, a shell fitted thereon, a series of number-keys, a zero-key, and means whereby said zero-key can be connected or disconnected from said shell.

30. In a mechanism of the class described, the combination of a key-shaft, a shell fitted thereon, a series of number-keys arranged on the shell, a hub, a zero-key fitted on said hub, operating connections extending from said

hub, and means whereby said hub can be connected or disconnected from the shell.

31. In a mechanism of the class described, the combination of a key-shaft, a shell mounted thereon, a series of number-keys mounted on the shell, a hub having operating connections extending therefrom, a zero-key mounted on said hub, a clutch for connecting said hub to said shell, said zero-key being cut away so that when said clutch is used to connect said hub to said shell an operation of any of the number-keys will not operate the zero-key.

32. In a machine of the class described, the combination with a shaft carrying a series of dials normally loosely revolute, a series of keys and means whereby the operation of a key will first lock a dial to the shaft and then turn that dial through the medium of the shaft a distance corresponding to the digital value of the key struck, means whereby the operation of each subsequent key will first release the preceding dial and then lock the adjacent dial before the shaft is turned, and means whereby as each dial passes zero the next adjacent loose dial will be advanced one space before it is locked to the shaft.

33. In a convertible adding and subtracting machine, a dial-shaft carrying a series of dials loosely mounted on the shaft a series of keys and means whereby the operation of a key will rotate the dial-shaft a distance corresponding with the digital value of the key struck, and means operated by the operation of a key to lock the first dial at one end of the series before the shaft is turned and the operation of each subsequent key will release said first dial and lock and turn the next adjacent dial and so on throughout each operation in addition, and reversed duplicate mechanisms whereby the operations in subtraction may be begun at the opposite end of the series of dials, substantially as set forth.

34. In a machine of the class described, the combination of a series of numbered spring-actuated keys, a dial-shaft and a series of dials loosely rotatable thereon, and means whereby the depression of a key will lock a dial to the shaft and its normal return will rotate said dial through the medium of the shaft a distance corresponding with the digital value of the key struck, substantially as set forth.

35. In a calculating-machine, the combination of a dial-shaft and a series of dials loosely rotatable thereon, a tubular support between each adjacent pair of dials, a clutch member mounted in each of these supports and adapted to engage and lock an adjacent dial to the shaft, a series of keys and means connected thereto for actuating the dial-shaft, a clutch-operating lever extending into each

of the tubular supports, and means whereby these clutch-operating levers are operated in succession by the depression of the keys, substantially as set forth.

36. In a calculating-machine, the combination of a dial-shaft carrying a series of loosely-rotatable dials and a loosely-rotatable pinion at each end of the shaft, reversed rack-bars connecting these pinions to the key-operated mechanism, a clutch member at each end of the shaft adapted to lock its adjacent pinion to the shaft, means for simultaneously shifting these clutches when the machine is to be converted from an adding-machine to a subtracting-machine and vice versa, and means whereby the dials are successively locked and unlocked, substantially as set forth.

37. In a calculating-machine, the combination of a series of numbered keys, a dial-shaft and devices whereby the operation of any key will rotate the dial-shaft a distance corresponding to the digital value of the key struck, a series of independent dials normally loosely revolute on the dial-shaft, and mechanism whereby a dial is first locked to the dial-shaft during a key operation and then turned and the operation of each subsequent key will first release the locked dial and then lock and turn the next adjacent dial, whereby one of the dials will remain locked to the shaft during each operation in addition or subtraction, said mechanism embodying a clutch for each dial, a shaft carrying a cam for each clutch, means whereby each cam operates one of the clutches, and means whereby the cam-shaft may be operated through the medium of the keys.

38. In a calculating-machine, the combination of a series of keys including a zero-key, a dial-shaft and devices connecting with the keys whereby the operation of any key will rotate the dial-shaft a distance corresponding to the digital value of the key operated, a series of independent dials rotatably mounted on the dial-shaft, mechanism whereby the dials are successively locked and unlocked by the operation of the keys, whereby one of the dials will always be locked to the shaft during each operation, and means whereby the dial locking and unlocking means may be disconnected from the number-keys and connected to the zero-key for converting the machine into a multiplying-machine.

In testimony whereof I have hereunto set my hand in the presence of two subscribing witnesses.

ARTHUR E. KENYON.
